UNITED STATES PATENT OFFICE.

EDWARD LASIUS PEACOCK, OF WALLSEND-ON-TYNE, ENGLAND.

SUBMARINE OR SUBMERSIBLE BOAT.

1,152,754.

Specification of Letters Patent. Patented Sept. 7, 1915.

Application filed January 26, 1915. Serial No. 4,495.

To all whom it may concern:

Be it known that I, EDWARD LASIUS PEACOCK, engineer, a subject of the King of Great Britain and Ireland, of Wallsend 5 Shipyard, Wallsend-on-Tyne, England, have invented certain new and useful Improvements in Submarines or Submersible Boats, of which the following is a specification.

- 10 The present invention relates to an arrangement of stern for a submarine or submersible boat of this kind which may oppose the smallest possible resistance to motion and which may give a cheap and easily dismountable construction. These conditions are not obtained where the propeller shaft bearings and struts are forward of the propeller and where the horizontal rudder located aft of the propeller is supported by 15 additional arms or struts which additional arms or struts I can eliminate through locating the shaft bearing aft of the propeller and use that bearing also as a support for the rudder.
- 20 25 The invention consists of a stern of a submarine or submersible boat having diving or horizontal rudder or rudders and propellers with their shafts and bearings and struts or supports for said bearings, and is characterized by the fact that the propeller shaft bearings are located aft of the propeller and are also used for supporting the diving or horizontal rudder or rudders which are supported not at their outboard edges as is generally done, but inboard of the outboard edge.
- 30 35 40 For the purpose of easily erecting or dismounting the propeller and shaft a detachable coupling is provided on the propeller shaft between the propeller and the ship so that it is possible to remove the propeller shaft together with the propeller without it being necessary to remove the strut boss or its struts. Further for the purpose of obtaining the smallest possible resistance to 45 motion through the water the horizontal struts carrying the propeller bearings are located in the same plane as and adjacent to the horizontal rudder, also the horizontal 50 strut and horizontal rudder are shaped in their sections to form one fair body to motion through the water.

On previous submarines where the struts are separate appendages it is necessary to 55 keep down the thickness to a certain proportion of its fore and aft length in order that the resistance to motion is not too great.

As now proposed with the struts and rudders forming one long fair body it is possible to considerably increase the section and 60 area of the horizontal strut and still keep the ratio of the combined length of the horizontal strut and rudder to the maximum thickness greater than is possible with the 65 separate struts as generally used. For this reason it will be possible to carry the propeller shaft bearing and horizontal rudder by one horizontal strut from the ship. While 70 this can be done this invention does not preclude the use of an additional strut or struts such as that marked *p* (in the drawing referred to below) if such are deemed necessary in some cases. For the purpose of still further reducing the resistance and increasing the efficiency of propulsion the forward 75 ends of the horizontal strut or struts and of the horizontal rudder are inclined or curved away from the geometrical plane passing through the axis of the propeller shaft so that the well known rotating stream line 80 passing aft from the propeller is gradually deflected to a horizontal flow by the horizontal strut and rudder. Figure 4 and Fig. 5 in the drawings referred to below show 85 diagrammatically such a change to the horizontal plane for an outward turning propeller which would be reverse to the inclination or curvature shown with an inboard turning propeller. Further the entire arrangement of the stern in combination with 90 the horizontal diving rudder or rudders and the vertical rudder and their struts and skegs is characterized by the fact that the rudders complete together with the said horizontal struts or vertical skeg a more or less 95 rectangular shape as is shown on the accompanying drawings, where:

Fig. 1 is a longitudinal section of stern of a submarine or submersible boat; Fig. 2 is a plan view; Fig. 3 is a cross section on line A—A; Fig. 4 is a fore and aft section on line B—B; Fig. 5 is a fore and aft section on line C—C.

The bearing part *a* of the propeller shaft *b* carrying propeller *c* is placed in the strut boss *d* fitted with a bearing *e*. In the strut boss *d* is fitted a journal *f* which forms the outer bearing of diving or horizontal rudder *g*. Both wings of the diving rudder are rigidly but removably connected together, 105 being preferably secured to a connecting member *h* which has its bearing in the skeg *j*. For dismounting the diving or horizontal rudder the wings must be disconnected 110

and removed out from journal *f*. The propeller strut bearing boss *d* is supported by the horizontal strut *h* which is supported from skeg *j* and also by an additional strut 5 or struts *p*. The skeg *j* supports also the vertical rudder *m*. For the purpose of dismounting the propeller shaft and the propeller the coupling *n* will be disconnected, and the horizontal rudder will be inclined 10 as much as is necessary for the removal aft of the bearing *e* from the strut boss *d* when the part *a* of the propeller shaft has space enough in the strut boss *d* so that the propeller shaft may be sufficiently inclined at 15 coupling *n* so that the shaft and propeller may be removed forward. The horizontal rudder may also be supported by bearing *f* from the strut boss *d* either above or below the center line of the shaft so that the bearing *e* can be removed aft from strut boss *d* without inclining the horizontal rudder or 20 rudders *g*. In either case the horizontal strut *h* would be located in line with the horizontal rudder. 25 In Fig. 4 is shown how the propeller hub with strut boss *d* and a special fair water *o* on the horizontal rudder are fitted to make a continuous fairwater and also how the horizontal strut fairs with the horizontal rudder and makes practically one continuous body. 30

This invention can also be used for submarines or submersible boats having three or more shafts in combination with some 35 propellers with propeller shaft bearing in accordance with this invention, and some as generally used with the propeller shaft bearing forward of the propeller.

What I claim and desire to secure by Letters Patent is:—

1. In submarine boats or submersible boats, a strut boss disposed in the stern of the boat, a shaft protruding through the hull of the boat to the strut boss, a propeller disposed on the shaft between the strut boss and the hull of the vessel, a diving rudder disposed to the rear of the strut boss and supported by the strut boss, one end of said shaft being also supported by the strut boss. 45
2. In submarine boats or submersible boats, a strut boss disposed in the stern of the boat, a shaft protruding through the hull of the boat to the strut boss, a propeller disposed on the shaft between the strut boss and the hull of the vessel, a diving rudder disposed to the rear of the strut boss and supported by the strut boss, one end of said shaft being also supported by the strut boss, 50 said diving rudder being pivoted inboard of its outboard edge and curved on its under surface. 55
3. In submarine boats or submersible boats, a strut boss disposed in the stern of

the boat, a shaft protruding through the hull of the boat to the strut boss, a propeller 65 disposed on the shaft between the strut boss and the hull of the vessel, a diving rudder disposed to the rear of the strut boss and supported by the strut boss, one end of said shaft being also supported by the strut boss, 70 said diving rudder being pivoted inboard of its outboard edge and curved on its under surface, said strut boss being supported by a bracket having a vertical skeg and horizontal strut. 75

4. In submarine boats or submersible boats, a strut boss disposed in the stern of the boat, a shaft protruding through the hull of the boat to the strut boss, a propeller disposed on the shaft between the strut boss 80 and the hull of the vessel, a diving rudder disposed to the rear of the strut boss and supported by the strut boss, one end of said shaft being also supported by the strut boss, said diving rudder being pivoted inboard of 85 its outboard edge and curved on its under surface, said strut boss being supported by a bracket having a vertical skeg and horizontal strut, said horizontal strut being curved on its upper surface and disposed in 90 the plane of the diving rudder.

5. In submarine boats or submersible boats, a strut boss disposed in the stern of the boat, a shaft protruding through the hull of the boat to the strut boss, a propeller 95 disposed on the shaft between the strut boss and the hull of the vessel, a diving rudder disposed to the rear of the strut boss and supported by the strut boss, one end of said shaft being also supported by the strut boss, 100 a coupling to said shaft disposed between the propeller and the hull.

6. In submarine boats or submersible boats, a strut boss disposed in the stern of the boat, a shaft protruding through the 105 hull of the boat to the strut boss, a propeller disposed on the shaft between the strut boss and the hull of the vessel, a diving rudder disposed to the rear of the strut boss and supported by the strut boss, one end of said 110 shaft being also supported by the strut boss, said diving rudder being pivoted inboard of its outboard edge, and curved on its under surface, said strut boss being supported by a bracket having a vertical skeg and horizontal strut and a vertical rudder, said vertical rudder being disposed in the plane of the said skeg. 115

In witness whereof, I have hereunto signed my name in the presence of two subscribing 120 witnesses.

EDWARD LASIUS PEACOCK.
